ABSTRACT

A high speed rotary filling machine is provided with means for sensing incoming empty containers before they are moved onto the turret of the filling machine. Each valve of the filling machine is provided with a movable cam follower and a latch for either arming the follower to open the valve, or disarming the follower to keep the valve closed, according to the presence or absence of an incoming empty container approaching the turret for subsequent alignment with that valve. Arming the follower is effected by a fixed cam lying in the path of the followers, and disarming the follower is effected by a power actuated cam adjacent the same path. Each filling valve, accordingly, is normally opened during the filling operation unless it has been previously disarmed.

NO CAN-NO FILL FOR HIGH SPEED ROTARY FILLING MACHINE

BACKGROUND OF THE INVENTION

The field of the present invention is in filling machines, particularly high speed rotary filling machines embodying no can-no fill devices for disabling a filling valve if no container is present when the valve would otherwise be opened. More particularly, the present invention is directed to the specific problem of a no can-no fill mechanism which is capable of operating at fill rates in the order of 2,000 or more containers per minute to disable any given filling valve (or valves) for which there is no empty container.

With general reference to prior art no can-no fill devices, some of which are summarized below, the following broad operating principles appear:

1. The containers directly actuate mechanical linkage associated with each valve to move a valve actuator into position to open the valve at the appropriate filling station.

2. The containers indirectly actuate a power mechanism for placing a movable valve operating member into the path of the actuator of the filling valve.

In both cases, the filling valves are normally closed, and must be opened for each container present for a filling operation.

Thus, in the no can-no fill device disclosed in the Knoll U.S. Pat. No. 3,040,787, issued on June 26, 1962, the rotary actuator for each valve is operated by movement past a pivoted actuator arm. If a container is present for filling, the container pivots a sensing arm which swings the actuator arm into a position to intercept the rotary valve actuator. While this arrangement may be suitable for relatively low speed operation, the system cannot be successfully operated at the high fill rates of which the present invention is capable, because the impact of the container with the sensing arm will increase to the point where the container will be damaged or broken, due to the inertia of the sensing arm, and/or the inertia will limit the system to relatively low speed operation.

Another prior art no can-no fill device is disclosed in the Galloway U.S. Pat. No. 2,770,404, issued on Nov. 13, 1956, wherein the filling valves are air operated. A movable can detector plate extends into the path of the containers. Each passing container strikes the plate, moving it to mechanically cause the sequential movement of a slideable sleeve, a pivotable bellcrank, a roller, a rod, and a cam. The cam is in turn contacted by part of an air control unit individual to each valve. With the many movable components in this system, the response time for opening the filling valves is appreciable, the system is complex to build and maintain, and the system may damage fragile containers if operated at the fill rates herein contemplated.

The Boucher U.S. Pat. No. 3,105,525, issued Oct. 1, 1963, discloses a no can-no fill mechanism for a filling machine having rotary valve actuators. Each container approaching the filling zone of the machine strikes a shoe mounted on the bottom end of a vertically extending lever which is pivoted between the shoe and a roller on the upper end of the lever. When the lever is pivoted by a container, the roller is moved into the path of the rotary actuator for the filling valve. This system has the disadvantage for high speed operation that the con-

tainer to shoe impact can damage the container, and the response time can only be shortened by increasing the impact.

In another type of no can-no fill device, the container is elevated for the filling operation, and the container lifts certain components which condition the valve to open, such as by placing a displaceable valve operating roller in position to engage a fill cam. The Taylor U.S. Pat. No. 874,874, issued Dec. 24, 1907, and the Dickerson U.S. Pat. No. 1,117,346, issued Nov. 14, 1917, show this type of arrangement. High speed operation utilizing this operating mode can damage the containers. In a similar type of device, elevating the container shifts a movable cam section into valve opening position; the Ayars U.S. Pat. No. 1,468,254 shows this operating mode. Another variation, shown in the Albrecht et al. U.S. Pat. No. 3,073,359, Jan. 15, 1963, is to employ a power-operated movable cam track wherein a container present for filling indirectly places the cam track in position to open the valve.

A later refinement in no can-no fill devices more suitable for high speed operation and for handling fragile containers is shown in Minard U.S. Pat. No. 3,139,915, issued July 7, 1964. In this patent, the containers are sensed by a photocell unit at the star wheel which feeds the containers to the turret. The photocell unit sets pins on an analog memory wheel to operate an air cylinder for positioning a shiftable cam section, as in the Albrecht et al. patent. Due to the sensing mode, the Minard structure is especially adapted to handle very fragile containers, of any desired shape.

While there are numerous other no can-no fill devices, it is believed that the devices above outlined are fairly typical and representative. The common denominator of some of these prior art systems, is that the container itself must provide a rapid reaction force to mechanically actuate the no can-no fill mechanism, and that the reaction force will increase drastically if the rate of container movement is increased. Further, the mode of operation is that a filling valve is normally inoperative and made operable for the prevailing condition of a container being present, whereas it is obviously more efficient that a filling valve be normally operable, and only periodically disabled, because the no container condition is infrequent. In some cases, centrifugal force can adversely affect the operation if the rotational speed of the turret is increased, because pivotable linkages are employed in which the pivot axis is not radially related to the turret.

A basic aspect of the present invention, with the primary objective being a capability of handling 2,000 or more containers per minute, is that the most efficient arrangement, in the type of filling valve which operates by axial movement of the valve core, is to maintain the filling valves in a normally ready condition for the more prevalent filling cycle, and to periodically disable a valve core lifting mechanism for the relatively infrequent occasions when a container is absent. Accordingly, a feature of the present invention is:

1. The lifter for each moving valve is always conditioned to open by one means for a filling operation, and is disabled by a second, structurally separate and remote means only if a container is absent.

Another aspect of the present invention is that because the incoming containers for a rotary filling machine turret are fed by a transfer star wheel operated in timed relation with the turret, the sensing of the pres-

ence of a container to be ultimately positioned under a filling valve can effectively and positively be detected at the transfer star wheel, before the container is fed to the turret, without any interposed memory device, such as in the aforementioned Minard U.S. Pat. No. 3,139,915, to control the opening of the filling valve. Accordingly, a feature of the present invention is:

2. A container detector is associated with the feed mechanism that operates in timed relation with the turret, and the timing is arranged so that the presence or absence of a container at the feed mechanism allows the detector ample time to directly operate the filling valve disabling mechanism for the valve corresponding to an absent container.

A further aspect of the invention is the useful exploitation of the fact that a filling valve operates by relative spatial motion with fixed structure of the filling machine. Accordingly, a further and more specific feature of the present invention is:

3. Each filling valve is provided with an actuator which is normally armed or preset by a fixed cam for the filling operation, and is only periodically disarmed and rendered inoperative for a filling operation by a movable, power operated cam in fixed location, and separate from any of the continuous cam tracks, whenever a container is absent from one of the container positions sensed by the container feed mechanism.

A further feature of the present invention is that the pivotable components carried by the valves are relatively unaffected by centrifugal force because their pivot axes are substantially radial relative to the turning axis of the turret on which the valves are mounted.

SUMMARY OF THE INVENTION

In accordance with the inventive concepts outlined above, the structural embodiment of those concepts includes fixed sensing means which scans the passing recesses of a star wheel that feeds empty containers in timed relation onto the turret of a high speed rotary filling machine. Each filling valve on the turret is actuated by a cam follower pivoted to a block which moves with the valves as the valve moves between open and closed positions. A latch is provided for locking the pivotally mounted cam follower to the block, or for releasing the cam follower for independent movement relative to the block. In effect, this locking or releasing of a cam follower is equivalent to arming or disarming the valve lifting mechanism, so that the valve will either open to fill a container, or will remain closed if no container is positioned beneath the valve. A fixed cam in the path of the latches sets or arms the previously disarmed cam followers to open the valves in the next filling cycle. Further downstream, a power actuated disarming cam is movable into the path of the latches to release or disarm a given cam follower in response to a "no-container" signal from the sensing means. Thus, only a single sensing means, and no complex additional valve mechanism is required, and the power energized-cam operated mode of operation provides a rapid response to the "no-container" signal so that extremely high filling rates are achieved with reliable no can-no fill operation. An important feature of the present invention is its fail safe mode of operation because it eliminates mechanisms which can jam the filling machine if a mal-function occurs in the no can-no fill components.

BRIEF DESCRIPTION OF THE DRAWINGS

FIG. 1 is a diagrammatic vertical section through a plunger-valve type of rotary filling machine.

5 FIG. 1A is an operational view of the right-hand valve shown in FIG. 1, but in a different operational position.

10 FIG. 2 is a fragmentary exploded isometric showing typical mechanism for selectively operating a filling valve according to the presence or absence of a container in filling position for that valve.

15 FIG. 3 is a diagrammatic horizontal section taken along lines 3-3 on FIG. 1.

20 FIGS. 4-6 are composite diagrammatic elevations and plans showing the sequential steps in disarming or inactivating a filling valve, and the correlated positions of a filling machine turret and a star wheel associated with the filling machine for feeding containers to the turret; the respective section lines for the upper portions of FIGS. 4-6 are indicated on FIG. 3.

25 FIGS. 7-10 are diagrammatic elevations similar to the corresponding portions of FIGS. 4-6, and illustrate further sequential operations of the valve actuating mechanism; the respective section lines for FIGS. 7-10 are shown on FIG. 3.

30 FIG. 11 is an enlarged section of a container sensing mechanism, and is taken along lines 11-11 on FIG. 3.

35 FIG. 12 is a view similar to FIG. 11, but with the empty container of FIG. 11 omitted.

40 FIG. 13 is a schematic plan showing the major operating components associated with the container sensing mechanism of FIGS. 11 and 12.

DESCRIPTION OF THE PREFERRED EMBODIMENT

The rotary filling machine 20 shown in FIG. 1 is of the general type disclosed in the previously mentioned Gollmer U.S. Pat. No. 2,307,214, in which the valves controlling the product dispensing function operate with axial motion. The type of filling machine disclosed in the Gollmer patent had an output of about 90-125 filled containers per minute, whereas depending on the product, the filling machine 20 is capable, with a 22-pocket turret and with certain products, of outputs over 2,000 filled containers per minute. However, due to speed limitations of a processing line, the actual filler output in commercial use may be somewhat smaller. Some no can-no fill mechanisms of the prior art are not capable of operation at such high output rates because of the inability of the structure to react fast enough, because centrifugal force impairs operation, or for other reasons. A no can-no fill mechanism is now an essentially standard part of modern high speed filling machines because if a defective container must be removed from the container supply line, or if the container feed is otherwise temporarily interrupted, the product intended for the missing container or containers is not only wasted, but will contaminate the machine and work area, and cause additional cleanup work.

With reference to FIGS. 1-3, the present invention concerns a no can-no fill mechanism comprising a valve control 22 associated with each filling valve assembly 24, a container sensing mechanism 26, a fixed arming cam 28 which lies in the path of the valve control 22, and a power operated disarming cam 30 which

is movable into the path of the valve control mechanism 22 and is responsive to the container sensing mechanism 26. The rotary filling machine 20 is of the type wherein the filling valves 24 operate with axial motion, and each filling valve is associated with positive displacement means for feeding a measured volume of product to the valve.

With more specific reference to the filling machine 20 (FIG. 1), which is conventional except for the no can-no fill mechanism, a fixed support pedestal or frame 32 supports a hollow cylindrical turret housing 34 that is rotatably mounted on a support bearing 36. A large gear 38 is secured to the lower end of the turret housing 34 and is meshed with a gear 40 driven by a gear box 42. The same gear box drives a shaft assembly 43, for a vertically superposed star wheel 44, in timed relation to the turret housing for feeding incoming empty containers C from an input conveyor belt 45 (FIG. 3) over a support track 46 to the filling machine. The belt 45 and an associated feed screw 47 are also driven by the gear box 42. For this purpose, a drive belt 49 from the gear box drives a second gear box 51 (FIG. 3) that directly drives the feed screw 47, and by a belt and pulley drive 53 powers the input conveyor belt 45. The pedestal 32 has upwardly extending standards, one of which is shown at 48, (FIG. 1) for supporting certain non-rotatable elements of the filling machine.

Fixed parts include an inclined plunger cam 50 which surrounds the lower portion of the turret housing 34 and is adjustable for inclination, two circular container support tracks 52, and an arcuate filling valve cam 56 at the upper end of the machine.

Parts which rotate with the turret housing 34 include a circumferential array of plunger displacement cylinders 58, the filling valves 24, an open-top product supply tank 60, and a peripherally recessed turret plate 62 which defines moving, semicircular pockets P (FIG. 3) for the containers C.

The plunger valve cylinders 58 communicate with the interior of the supply tank 60 during part of their circular path, and in another part move under and are sealed by a fixed slider plate 63. Accordingly, product from the supply tank 60 (FIG. 1) fills each plunger valve cylinder 58, as shown for the valve 24 at the right side of FIG. 1, to the top of a piston 64 which is slideable in the cylinder. For reciprocating the pistons 64, the plunger cam 50 is engaged by a cam follower unit 66, for each piston. Each cam follower unit is slideably mounted for vertical movement in a guide assembly 68, which is secured to the rotatable turret housing 34, and is connected to the piston by a piston rod 70. The piston rod is mounted on the follower unit 66 to prevent rotation of the piston so that the inclined top surface of the piston always declines toward the filling valve 24. It will be evident that the adjusted position of the plunger cam 50 determines the volume of product admitted to the plunger valve cylinder 58.

With continued unitary rotation of a plunger valve cylinder 58, an adjacent empty container C, and one of the filling valves 24 vertically aligned with the container, the plunger valve cylinder 58 is sealed as it slides under the slider plate 63. This position is comparable to that shown for the valve 24 at the left side of FIG. 1 wherein it will be seen that the slider plate 63 closes the upper end of the plunger valve cylinder 58. The plunger cam 50 then begins to raise the plunger valve piston 64 for transferring the product into the con-

tainer. At this time, the filling valve 24 is opened, having been moved to open position by the filling valve cam 56 because a container C is present for the filling operation. As will be described, if no container is present, the no can-no fill apparatus of the present invention disables the filling valve so that, even though the cam 56 reacts with the filling valve in the usual way, the ports of the valve remain closed.

Each filling valve 24 includes a cast housing 80 (FIG. 1) having an inlet passage 82, an outlet passage 84, a cylindrical valve core 86 vertically slideable in the housing, and an open lower end 87 through which the product is transferred to the underlying container. An arcuate recess 88 in the valve core 86 is arranged to periodically interconnect the inlet and outlet passages 82 and 84. It will be seen that the upper portions of the plunger valve cylinders 58 are formed by a valve ring 90 having lateral passages 92 which each align with one of the filling valve outlet passages 84. In the right-hand filling valve 24 of FIG. 1, the bottom end of the valve core 86 lies just above the outlet passage 84, and the lifting of the piston 64 will force the product from the plunger valve cylinder 58 through the passages 92 and 84, and out the open bottom end 87 of the valve housing 80 into the container C.

If the valve core 86 (FIG. 1A) is lowered to seal off the passage 84 from the container C shown in phantom, the arcuate recess 88 interconnects the passages 82 and 84, and a subsequent raising of the plunger valve piston 64 will force the product through the passages 92, 84, 88 and 82 back into the supply tank 60. This is the operational sequence which results when the no can-no fill mechanism of the present invention senses the absence of a container C in fill position for each filling valve 24 approaching the filling zone of the filling machine; the appropriate filling valve 24 will be disabled as described above, and the product intended for the absent container will be returned to the supply tank 60.

With reference to FIGS. 2 and 4, the upper end of the filling valve core 86 is provided with an integral flanged head 94 which in the assembled valve fits into a corresponding recess 96 in a slide block 98. Thus, the recess 96, best shown in FIGS. 7-10, has a form substantially complementary to the flanged head 94 (FIG. 2) to lock the assembled block 98 and head 94 together for coextensive vertical movement. The slide block 98 is a part of the valve control mechanism 22 of the present invention, and in turn, is slideable upon two fixed guide bars 100 that extend upward from the valve housing 80. In order to selectively open or close the filling valve 24 in the manner and for the purpose above described, a pivotally mounted cam follower roller 102 is carried by the slide block 98 and rides on the filling valve cam 56. The follower roller 102 can be locked to the slide block 98 so that the slide block and the valve core 86 rise and fall with the elevational changes in the cam 56 to open and close the filling valve. Alternatively, the cam follower roller 102 can be unlocked from the slide block 98 so that the elevational changes in the cam 56 will pivot the roller 102 but leave the slide block 98 and the valve core 86 at their lowermost positions, wherein the filling valve 24 will remain closed.

For selectively operating the filling valve 24, the cam follower roller 102 is mounted on a pivotable carrier lever 104, the pivot of which comprises an integral bolt 106 extending through the slide block 98. A laterally

extending stop abutment 107 (FIG. 2) on the lever 104 limits the downward movement of the lever 104 by engaging an edge of the slide block. The slide block 98 also carries a pivotable latch or pawl 108 mounted on an integral pivot bolt 110. In the same manner as the lever 104, the latch 108 is provided with a lateral abutment 112 for limiting downward movement of the latch. Projecting in the opposite direction from one end of the latch 108 is a laterally extending cam 114 having an upper camming surface and a lower camming surface. The upper camming surface is arranged to slide under the fixed arming cam 28 (FIGS. 3 and 10) to lock the follower roller 102 to the slide block 98, and the lower camming surface is arranged to slide over the disarming cam 30 (FIGS. 5 and 6) to unlock the roller 102 from the slide block 98 so that elevation of the follower roller 102 by the filler valve cam 56 will not lift the valve core 86. In effect, therefore, the respective upper and lower camming surfaces of the cam 114, and the cams with which they cooperate, arm and disarm the associated filler valve 24, because in the first instance the follower roller 102 can lift and open the valve core 86 of the filler valve, whereas in the second instance elevation of the roller 102 cannot change the closed condition of the valve.

With reference to FIG. 4, the other end of the latch 108 has an end portion 120 which is arranged to engage an abutment portion 122 of the carrier lever 104. This is the armed position of each valve control mechanism 22 when it approaches the disarming cam 30 (FIGS. 1 and 4). As shown in the bottom portion of FIG. 4, it is assumed for the operational sequence to be later described that in an incoming series of containers C1-C8, container C3 is missing due to some upstream condition, such as its removal because of damage. The star wheel 44 carries the incoming containers, in timed relation with the rotary turret of the filling machine, past the container sensing mechanism 26 (FIG. 3) to determine the presence or absence of a container for each recess of the star wheel. A fixed, curved guide bar 126 maintains the containers centered over the adjacent container support track 46.

FIGS. 11 and 12 respectively illustrate the container sensing mechanism 26 in the operative positions resulting from the presence of a container and the absence of a container. A hinge block 124 (also see FIG. 3) is secured to the guide bar 126. A pivot bolt 128 extends through the hinge block and through a depending swing block 130. The block 130 carries a container sensing plate 132 having an arcuate inner edge 134 (FIG. 3) arranged to be contacted by each container carried past by the star wheel 44.

Underlying the sensing plate 132, FIGS. 11-13, are two air valves 136, 137. Each air valve is provided with a pivoted actuator lever 138, having a roller engaged with the underside of the sensing plate 132, and arranged to operate a valve plunger 139 (FIG. 13). The plungers 139 are spring biased upward so that the sensing plate 132 is biased toward its FIG. 12 position. A container sliding against the surface 134 of the sensing plate 132 will simultaneously effect the depression of both valve plungers 139. Each valve 136 and 137 includes an air inlet conduit 140, and an air outlet conduit 142. The two inlet conduits 140 are connected to an air pressure supply line, not shown, and the two outlet conduits 142 are connected to a double-acting air cylinder 144 (also shown in FIGS. 5 and 6) to power

the disarming cam 30 in both the up and down directions. A bracket 145 (FIGS. 11 and 12) depends from the support track 46 and mounts the valves 136 and 137. The valve actuating levers 138 are simultaneously operated by the sensing plate 132, the air valve 137 being normally open and the air valve 136 being normally closed when the actuators 138 are not depressed. As shown in FIGS. 5 and 6, the air cylinder 144 is mounted on the vertical leg of an angle bracket 146 which depends from the filling valve cam 56, and the disarming cam 30 (FIG. 3) extends inward of the filling valve cam in the path of the latch arm cam 114 (FIG. 5). To prevent rotation of the disarming cam 30, it slides against the vertical leg of the angle bracket 146. It will be evident that conventional venting means, not shown, are provided to bleed air from either end of the cylinder 144 when the opposite end is energized.

With reference to FIG. 4, the cam 114 for the filling valve V3 is in position to be contacted by the disarming cam 30 if the air cylinder 144 is energized to elevate the cam 30.

The containers C5, C6, C7 and C8 in FIG. 4 have maintained the container sensing plate 132 in the FIG. 11 position, and the air valve 136 (FIG. 13) has held the disarming cam 30 in its lowermost, retracted position. Thus, the air cylinder 144 is only energized to project the disarming cam upward into the path of the cam 114 for the particular filling valve which corresponds to an empty recess in the star wheel 44. In the present instance, this is the filling valve V3 (FIG. 5), corresponding to the absent container C3.

In FIG. 5, the container C4 has moved against the container sensing plate 132. As shown by the phantom lines, container C5 does not leave contact with the plate 132 until after the container C4 has engaged the plate. Thus, when there is no gap in the supply of containers in the star wheel, there is no change in the condition of the air cylinder 144 and the retracted position of the disarming cam 30. As seen in the upper portion of FIG. 5 for the valve V3, the roller 102 of the valve control mechanism 22 has been elevated a slight amount on an upwardly inclined ramp portion 148 of the filler valve cam 56. This elevating movement is not sufficient to open the filling valve, and is for the purpose of preconditioning the armed latch 108 to prevent re-engagement of the latch 108 with the follower carrier 104 when valve V3 is disarmed by the disarming cam 30, as will be next described.

As soon as the container C4 is carried by the star wheel 44 past the container sensing plate 132, the plate is free to swing toward the axis of the star wheel because the pocket which would have received a container in the (C3) position is empty. Accordingly, the air valve 136 (FIG. 13) closes, the air valve 137 opens, and the piston of the air cylinder 144 is actuated to raise the disarming cam 30 into the path of the cam 114 to pivot the latch 108 clockwise, as shown in FIG. 6. Because the roller 102 is elevated slightly as it moves up the ramp 148 (FIG. 5), a gravitational bias tending to pivot the carrier lever 104 clockwise about its pivot 106 is created due to the weight of the slide block 98, the valve core 86 attached to the slide block, and other parts that are supported by the roller 102.

Thus, when the disarming cam 30 is elevated as previously described, the instantaneous operation shown in FIG. 6 occurs; the cam 114 contacts the disarming cam 30 and pivots the latch 108 so that it disengages

the carrier lever 104. As soon as the carrier lever 104 is free of the latch 108, the weight of the slide block 98, the valve core 86 attached to the slide block, and other parts, causes the slide block 98 to immediately drop to the FIG. 7 position. Since the follower roller 102 (FIG. 6) is supported by the filling valve cam 56, the result is that the follower carrier lever 104 is immediately pivoted clockwise from the FIG. 6 to the FIG. 7 position so that the latch arm 108 cannot under any circumstances reestablish locking relation with the carrier lever 104. The valve operating mechanism for the valve V3 is now positively disarmed.

When the valve V3 (FIG. 6) and the pocket P3 move into container-transfer relation to the star wheel recess from which the container C3 is absent, the follower roller 102 (FIG. 8) has traveled up a ramp 150 onto an elevated track section 152 of the filling valve cam 56. It is clear that if the latch arm 108 had not been released from engagement with the follower carrier lever 104, the slide block 98 would have been elevated to lift the valve core 86 and open the filling valve V3. However, in the present case where the valve V3 must be kept closed because of the absence of the container C3, the ramp section 150 merely pivots the follower carrier lever 104 upward about its pivot bolt 106 without elevating the slide block 98. The valve core 86 (FIG. 1A) thus remains in its lowermost, closed position, and the valve passage 88 returns the product to the product supply tank 60 when the filling or plunger piston 64 (FIG. 1) is elevated by the inclined plunger cam 50.

The track section 152 (FIG. 9) merges with a descending ramp 154, and a level portion 156 near the end of the filling valve cam 56, at which the reset cam 28 (FIG. 10) positively returns the latch components to the latched position shown in FIG. 4. However, the carrier lever 104 is overbalanced so that it will normally push the latch arm 108 aside and reset the latch before the FIG. 10 position is reached. If not, the reset cam 28 makes this reset action positive.

As mentioned, if the latch arm 108 of any filling valve does not engage the disarming cam 30 (FIGS. 4 and 5) the filling valve will remain in the normally operative position of FIG. 4, through the full rotation of the filling machine turret. Thus, the valve will be opened and remain open while traversing the elevated track section 152.

To summarize, the machine functions which will keep a valve armed for a normal filling operation of course initiate with the container sensing mechanism 26 (FIG. 1). If a container is present at the sensing station, the disarming cam 30 (FIG. 5) will remain in its down position out of the path of the cam 114 on the latch arm 108, and the valve control mechanism 22 will remain in its latched or armed position. Then, when the follower roller 102 is carried up the ramp section 150 (FIG. 8) the slide block 98 will be elevated to raise the valve core 86 to the open position illustrated in FIG. 1. The plunger piston 64 then rises and forces the product from the plunger valve cylinder 58 through the passages 92 and 84 out of the open bottom end 87 of the valve housing 80 into the container C aligned with that valve.

In accordance with the previously enumerated features of the present invention, it will be evident that with the described container sensing and valve manipulating operations, each filling valve lifting mechanism is normally armed to open the valve 24 for a container

filling operation, and disarmed to permit the valve 24 to remain closed for a fill-bypassing operation, both the arming and disarming being controlled by container sensing means apart from the turret. Further, in contrast to prior no can-no fill devices, the valve control mechanism of the present system is not affected by centrifugal force, and has no components which can jam or damage the filling machine in the event of a malfunction; the worst consequence of a malfunction is that a filling valve which is supposed to remain closed might discharge its contents.

A further useful aspect of the present invention concerns the container sensing mode. By locating the container sensing apparatus 26 adjacent the star wheel 44, rather than on the turret of the filling machine 20, and by keeping it physically separate from the valve actuating mechanism, it now becomes feasible to employ photoelectric sensing, or any other sensing system which requires little or no contact with a container, but without requiring a memory device to correlate the container sensing with the filling valves on the turret. It will be recognized, therefore, that the no can-no fill system of the present invention is compatible with very fragile containers, such as glass or aluminum, because the containers need not be impacted and possibly damaged to detect their presence.

Although the best mode contemplated for carrying out the present invention has been herein shown and described, it will be apparent that modification and variation may be made without departing from what is regarded to be the subject matter of the invention.

What is claimed is:

1. In a rotary filling machine of the type including valves each having an externally operated valve core for opening and closing ports in the housing of the valve and a no can-no fill mechanism; the improvement in said no can-no fill mechanism comprising external mounting means rigidly connected to the valve core; valve operating means displaceably connected to said mounting means for movement with or relative thereto; and latching means on said mounting means for selective engagement or disengagement with said valve operating means; said engagement locking said valve operating means to arm said mounting means for unitary movement of said valve operating means, said mounting means and said valve core; said disengagement disarming said valve operating means for movement relative to said mounting means, and means for disarming said valve operating means when no can is presented to the associated filler valve.

2. Apparatus according to claim 1, wherein said disarming means comprises movable camming means fixed adjacent the path of said latching means, and means for selectively moving said camming means to intercept and actuate said latching means to disarm said valve operating means.

3. In a rotary filling machine of the type including a container feeding star wheel, turret mounted valves each having a vertically movable valve core for opening or closing ports in the housing of the valve and a no can-no fill mechanism, the improvement in said no can-no fill mechanism comprising an external block connected to the valve core, a cam follower displaceably connected to said block for selective movement of said cam follower with or relative to said block, and a latch mounted on said block for selective engagement or disengagement with said cam follower, engagement of

said latch with said cam follower locking said cam follower to said block for unitary movement of the follower, block and valve core, disengagement of said latch freeing said cam follower for movement relative to the block, and means for disengaging said latch from said cam follower when a can is presented to the associated filler valve.

4. Apparatus according to claim 3, wherein said latch disengaging means comprises a movable arming cam adjacent the path of said latch, power means for moving said arming cam to intercept and actuate said latch to a position wherein said cam follower is disengaged for movement independent of said block, and control means remote from said turret including means for sensing the presence or absence of a container and means for controlling said arming cam accordingly.

5. The apparatus of claim 4, wherein said container sensing means is disposed at said star wheel.

6. In a rotary filling machine carrying a circular array of valves in filling relation with open containers, the valves being individually movable between open and closed positions, and a no can-no fill mechanism comprising mounting means connected to each valve for movement therewith, movable follower means carried by said mounting means, latch means on said mounting means for selectively locking said follower means for movement with said mounting means or unlocking said follower means for movement relative to said mounting means, means for sensing the presence or absence of an empty incoming container, and latch operating means responsive to said sensing means for actuating said latch to unlock said follower means when no container is presented to the associated filling valve.

7. In a container filling machine including a rotary turret carrying a circular array of filling valves in filling relation with open containers, the valves being movable by individual cam followers between open and closed positions, and a no can-no fill mechanism; the improvement in said no can-no fill mechanism comprising a block connected to each valve for movement therewith, means mounting said cam follower on said block for selective movement with or relative to said block,

a latch mounted on said block for selectively locking said cam follower for movement with said block or for unlocking said cam follower for movement relative to said block, means for sensing the presence or absence of an empty incoming container, and means responsive to said sensing means for unlocking said latch in the absence of an empty incoming container corresponding to the associated filling valve.

8. Apparatus according to claim 7 wherein said latch operating means comprises power means, and a latch cam movable by said power means into the path of said latch.

9. Apparatus according to claim 8 and means pivoting said latch arm to said block, said latch arm being overbalanced to engage said cam follower, said cam follower being normally locked for movement with said block by said latch arm.

10. Apparatus according to claim 9 and a first cam surface on the overbalanced end of said latch arm, said cam surface being engageable with said latch cam to unlock said latch arm.

11. Apparatus according to claim 10 and a second cam surface on the overbalanced end of said latch arm, and a static locking cam in the path of said second camming surface to reset said latch arm to lock said cam follower following the unlocking of said latch arm by said latch operating means.

12. Apparatus according to claim 11 wherein said cam follower includes a cam roller, a follower arm carrying said cam roller, and a pivot shaft connecting said follower arm to said block, said follower arm having an abutment surface engageable by said latch arm to prevent pivotal movement of said follower arm about the axis of said pivot shaft.

13. Apparatus according to claim 12 and means for feeding a spaced series of incoming empty containers to the turret, said feeding means operating in timed relation to said turret so that a container in said feeding means is correlated to an eventual position on the turret, and means mounting said container sensing means to scan the incoming containers in said feeding means before delivery to the turret.
